No. 790,686.

PATENTED MAY 23, 1905.

A. J. JOHNSON.

PLOW.

APPLICATION FILED DEO. 24, 1904.

UNITED STATES PATENT OFFICE.

ANDREW J. JOHNSON, OF CURIA, ARKANSAS.

PLOW.

SPECIFICATION forming part of Letters Patent No. 790,686, dated May 23, 1905.

Application filed December 24, 1904. Serial No. 238,198.

To all whom it may concern:

Be it known that I, ANDREW J. JOHNSON, a citizen of the United States, residing at Curia, in the county of Independence and State of Arkansas, have invented a new and useful Plow, of which the following is a specification.

This invention relates to plows of the class wherein a rotative cutting member is employed to produce the pulverization of the soil, and has for its object to improve the construction of such devices and increase the efficiency and at the same time reduce the expense of manufacture.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings, Figure 1 is a longitudinal sectional elevation. Fig. 2 is a plan view, partially in section, of the improved device. Fig. 3 is a sectional detail of the releasing mechanism. Fig. 4 is a sectional detail, enlarged, of the combined tool-box and adjustable seat-standard support.

The improved implement comprises an axle 10, having bearing-wheels 11 12 mounted for rotation thereon and provided with ratchet-hubs 13 14 for engagement by spring-controlled pawls fast to the axle and partaking of its motion, so that when the wheels move forward the axle will be rotated with them, but will not be moved when the wheels run backwardly, as will be obvious.

The ratchet-hubs and pawls are alike at both sides of the device; but for the purpose of

illustration one only of the same is illustrated 50 at 15 in Fig. 2.

Mounted to swing upon the axle 10 is a frame 16, carrying the draft-tongue 17, the latter extending forwardly of the axle and at one side of its center, so that the draft-animals 55 will travel upon the unplowed land, as hereinafter explained.

Mounted to swing upon the axle 10 and extending rearwardly of the same is a frame formed of spaced side members 18 19 and 60 transverse members 20 and having a shaft 21 mounted for rotation upon the side members. The shaft 21 is provided with spaced hubs 22 23, having radiating arms 24 25 connected at their outer ends by cutting-blades 26, the latter disposed parallel to the shaft and its hubs. The hubs, arms, and cutting-blades thus form an open drum having spaced peripheral cutting-blades, as shown.

Mounted to move longitudinally upon the 7c axle 10 is a gear 27, caused to partake of its rotary motion, as by a feather-key 28 on the axle fitting a corresponding channel in the hub 29 of the wheel in the usual manner. The wheel 27 is adapted to be moved longitudinally of the axle by a shipper-lever 30, mounted for longitudinal movement upon the tongue-frame 16 through a keeper 31, attached to the tongue-frame, the lever having spaced notches 32 33 for engaging the 75 keeper to support the lever in either one of its two positions, and the inner end of the rod 30 will be upturned, as at 39, and located convenient to the foot of the operator.

The gear 27 engages a pinion 34 on a stub-shaft 35, attached rigidly to the frame member 18, the pinion having a larger gear 36 integral therewith and engaging a pinion 37 on the shaft 21. By this arrangement it will be obvious that when the shipper-lever 30 is in 85 one position the gear 27 will be in mesh with the pinion 34 and rapidly rotate the shaft 21 and its cutting-drum as the machine is drawn forward, and when the shipper-lever is moved into its other position the gear 27 will be disconnected from the pinion 34, thus cutting off connection between the drum and the axle. Connected, as by bolts 48, to the frame 16 90 95

above the draft-tongue 17 is a tool-box 49, having inclined sockets 50 51 to alternately receive the standard 52 of the driver's seat 38, the standard being held in place, as by 5 set-screws 53 54. By this means the seat may be adjusted to provide means whereby the weight of the driver may be utilized to increase or decrease the tension upon the cutting-drum, as will be obvious.

10 Pivottally attached to the frame 16, as at 40, is a lever 41, having a pawl 42 for engagement with a notched segment 43, and the cutting-drum is provided with a housing or cover 44, attached to the transverse members 20 of 15 the cutting-drum frame and firmly supported by a relatively heavy arched frame member 45, having a central lug 46, between which and the lever 41 a connecting-rod 47 extends.

By this arrangement it will be obvious that 20 the cutting-drum frame is adjustably supported relative to the draft-tongue and its frame and may be adjusted to cut any desired depth or elevated entirely free from the ground, as may be required.

25 As before stated, the draft-tongue is located at one side of the center, so that the horses will travel upon the unplowed land, and as they move forward the cutting-drum is rapidly revolved, thoroughly pulverizing the 30 earth and leaving it in proper condition for planting without further attention.

With a plow thus constructed harrowing or further reducing will not be required, as the soil is so thoroughly pulverized as not to 35 require the use of such implements. The labor of preparing the soil for the crops is thus very materially reduced, and the soil placed

in a much better condition than by the use of the ordinary plow.

The machine may be constructed of any size 40 or capacity and of any suitable material, and any number of the blades 26 may be employed upon the cutting-drum.

Having thus described the invention, what is claimed is—

45 In an implement of the class described, an axle having transporting-wheels, a frame mounted to swing upon the axle extending forwardly of the same and having a draft-tongue, a frame mounted to swing upon the 50 axle and extending rearwardly of the same, a member mounted for rotation upon the rearward-extending frame, earth-engaging cutting-blades connected with said rotary member, means for transmitting motion from one 55 of the transporting-wheels to the rotary member, a housing for said rotary member mounted upon the swinging rear frame, a reinforcing member for said housing having an upwardly-extending arm said reinforcing member 60 being securely connected with the housing and with the supporting-frame, a hand-lever fulcrumed upon the front frame, a link connecting said lever with the arm extending from the reinforcement of the housing, and 65 means for retaining the lever at various adjustments.

In testimony that I claim the foregoing as my own I have hereto affixed my signature in the presence of two witnesses.

ANDREW J. JOHNSON.
